F. T. MATTHEWS
DEVICE FOR USE IN TRANSMITTING SIGNALS IN CONNECTION WITH FIRE
AND BURGLAR ALARM SYSTEMS AND THE LIKE
Filed Sept. 7, 1927

The diagram illustrates a complex linkage mechanism. It features a rectangular frame with a central vertical rod. A horizontal rod is attached to the left side of the frame. A diagonal rod connects the top of the frame to the horizontal rod. A curved dashed line, labeled D^3 , represents a path or trajectory within the mechanism. Points labeled D^4 , D^5 , and D^6 are marked along this curve. Other points labeled include D^1 , D^2 , E^1 , C , A , and A^3 . The mechanism includes various linkages and joints, with some parts shown in solid lines and others in dashed lines.

UNITED STATES PATENT OFFICE.

FRED THOMAS MATTHEWS, OF BRISBANE, AUSTRALIA.

DEVICE FOR USE IN TRANSMITTING SIGNALS IN CONNECTION WITH FIRE AND BURGLAR ALARM SYSTEMS AND THE LIKE.

Application filed September 7, 1927, Serial No. 218,062, and in Australia April 22, 1926.

This invention relates to devices used in transmitting signals, as in the case of fire alarms and such like. As at present arranged and wired, it is possible for the alarm 5 device to be operated when certain faults occur, in which case the signal would not be sent through to the indicator board, and, further, such fault would not show itself until the device and line had been tested at the 10 periodical inspection. The object of this invention is to provide means whereby the desired signal may be transmitted, and whereby, except in exceptional circumstances, a signal is always transmitted, and whereby it 15 is possible to ascertain which line is faulty. My invention relates more particularly to the arrangement of two circuits, one wholly metallic and the other metallic and earth. These circuits could be arranged to operate 20 with any known signal operating device and indicator, but preferably with the signal operating device and indicator hereinafter described and referred to.

In carrying out my invention I provide 25 devices and electric circuits whereby intermittent signals are transmitted from a signal box along wholly metallic and metallic and earth circuits to primary and secondary indicators on the indicator board.

30 In order that the invention may be better understood I will now describe it with the aid of the accompanying drawings, in which

Fig. 1 is a diagram showing one arrangement.

35 Fig. 2 is a detail showing one modification of a transmitter.

Figures 3, 3^a and 3^b show respectively circuits according to Figure 1 arranged separately in diagrammatic form.

40 Fig. 2 shows a transmitter for transmitting signals which I prefer to use, a lever D pivoted on the frame C may be arranged so as to be operated by the projections A¹. The lever D is provided with contact springs D¹ 45 D², which are thereby caused to make and break contact with electric terminals E E¹.

As will be seen in Fig. 2, the mechanism for operating the parts as shown in Fig. 1 is held in check by the lever D³ engaging the 50 projection D⁴ on the wheel D⁵ of the mechanism. Such lever D³ is operated, when it is desired to release the mechanism, by the button D⁶.

The disc A is grounded to the frame C,

and leads are provided from the terminals E 55 E¹ and from the frame C to the indicator board in the exchange or fire station, or as the case may be, as will hereinafter be described.

I prefer to arrange the circuits, as shown 60 in Fig. 1, as follows:—A line K is laid from one terminal E of the make and break of the alarm device to one terminal of the main indicator G.

A line M is laid from the other terminal 65 E¹ of the make and break of the alarm device to one terminal of the secondary indicator G¹. The other terminal of the secondary indicator G¹ is connected to a secondary battery N by line S, the other terminal of which is connected to earth. A line T from the other terminal of the main indicator G leads to a main battery L, the other terminal of which is connected to a line S leading from the secondary indicator G¹ to 70 the secondary battery N.

Fault clearing keys Q Q¹ Q² are provided in the three circuits for use when testing the lines.

When all lines are in order, the code telegraph alarm signal is transmitted from the alarm device through both circuits, and the main and secondary indicators are operated, but, should there be any fault on either line, the particular indicator connected to that 75 line would not operate.

According to Fig. 1, circuits are provided as follows:—

Earth circuit No. 1 (Fig. 3)—From frame C to earth, and thence through battery N, to 90 indicator G¹, and by line M, to terminal E¹, and by spring contact D² to frame C.

Earth circuit No. 2 (Fig. 3^a)—From frame C to earth, and thence through batteries N and L to indicator G, and by line K to terminal E, and by spring contacts D¹ to frame C. 95

Metallic circuit No. 3 (Fig. 3^b)—From terminal E by line K, to indicator G by line T to battery L and line S to indicator G¹, and thence by line M to terminal E¹ and by 100 spring contacts D² and D¹ to terminal E.

It will be readily seen from the foregoing that, should any fault occur on either of the lines, it will readily show itself and such line can be cut out by operating the particular fault clearing keys Q Q¹ Q² until such time as it is possible to rectify the fault. At the same time, it is still possible for an 105

alarm to be transmitted on either of the good circuits through either the main or secondary indicators, as the case may be.

The following faults and clearing operations may be given by way of example:—

Referring to Fig. 1—

1. Short circuit on lines K and M.—Indicators G and G¹ drop and fault is cleared by opening either Q or Q¹. The call is received through earth and line not broken by fault clearing key operating G or G¹.
- 10 2. Short circuit on lines K and M and open circuit on line M.—The call is received through earth and line K operating indicator G.
- 15 3. Short circuit on lines K and M and open circuit on line K.—The call is received through earth and line M operating indicator G¹.
- 20 4. Open circuit on line K.—The call is received through earth and line M operating indicator G¹.
- 25 5. Open circuit on line M.—The call is received through earth and line K operating indicator G.
- 30 6. Earth fault on line K.—Indicator G drops and fault is cleared by opening key Q¹. The call is received through earth and line M operating indicator G¹.
- 35 7. Earth fault on line M.—Indicator G¹ drops and fault is cleared by opening key Q.

The call is received through earth and line K operating indicator G.

It is highly possible that one of the batteries in the system may fail or go dead and if such occurs the system takes care of this possibility by virtue of the arrangement of the batteries. If one of the batteries fail there will still remain two systems over which the signals may be transmitted.

Having now particularly described and ascertained the nature of my said invention and in what manner the same is to be performed, I declare that what I claim is:—

In a normally open circuit signal system, a central station having a main indicator and a secondary indicator, a transmitter comprising make and break means normally maintaining said circuit open, a metallic circuit including said transmitter, said indicators and a source of electric supply, a combined metallic and ground circuit including said transmitter, one of said indicators and a second source of electrical supply and a second combined metallic and ground circuit including said transmitter, the other one of said indicators, and both of said sources of electrical supply.

In testimony whereof I have signed my name to this specification.

FRED THOMAS MATTHEWS.
